DIRECTIVE LOOP ANTENNA

Harold A. Wheeler, Great Neck, N. Y., assignor
to Hazeltine Research, Inc., Chicago, Ill., a cor-
poration of Illinois

Application August 27, 1946, Serial No. 693,267

8 Claims. (Cl. 250—33.51)

1

This invention relates to a loop antenna system that is directive in the plane of its conductors.

Loop antennas, as such, are very well known in the art. One common arrangement comprises four coplanar radiating conductors, each about one-half wave length in length, positioned to define a parallelogram or loop with open corners. A feed line is connected to the conductor ends at one corner of the loop and is connected with reversed phase to the conductor ends at the opposite corner of the loop. The currents are then in phase in all radiating conductors and produce a radiation pattern that is substantially uniform or omnidirectional in the plane of the loop. A system of this type, having four independent radiators, may be inconvenient to support and has substantially no directivity, whereas in certain installations the use of a directive loop antenna may be highly desirable.

It is an object of the present invention, therefore, to provide a loop antenna system which avoids the aforementioned limitations of prior arrangements.

It is another object of the invention to provide a new and improved loop antenna system which is directive in the plane of the loop.

It is a further object of the invention to provide a new and improved loop antenna system which has a simplified mechanical construction and is directional in the plane of the loop.

In accordance with the invention, a resonant directive loop antenna system comprises a pair of similar, coplanar radiating conductors of V-shaped configuration. The conductors have an effective diameter which is within the range from one-tenth to one-fortieth of the operating wave length, and they are disposed in image relation with reference to a plane of symmetry with the ends of one spaced from the ends of the other. One pair of the adjacent ends of the conductors have a highly reflecting termination and arms of each conductor individually define an acute angle and have an electrical length within the range from three-eighths to three-sixteenths of the operating wave length. The system includes means for connecting signal-translating apparatus to the antenna at the other pair of the adjacent ends of its conductors, whereby the antenna system exhibits minimum radiation in the direc-

tion of the opposite pair of adjacent ends of the conductors.

In constructing loop antenna systems, the radiating conductors may constitute sections of conductive pipes or, if desired, they may be the same lengths of flat metallic strips or ribbons, including one or several parallel-connected conductors. These alternatives are equivalent, insofar as the radiation properties of the antenna system are concerned. In converting from one type of construction to the other as, for example, in substituting conductive ribbons for pipe sections, the ribbon width is selected to be equal to twice the pipe diameter. In view of the equivalency of these conductor elements and the relation of their critical dimensions, the expression "effective diameter" as utilized in this specification and in the appended claims is intended to be generic and to define a conductive pipe of a recited diameter or a metallic ribbon having a width of twice that diameter or other equivalents.

For a better understanding of the present invention, together with other and further objects thereof, reference is had to the following description taken in connection with the accompanying drawing, and its scope will be pointed out in the appended claims.

In the drawing, Fig. 1 represents a plan view of a loop antenna system embodying the invention; Fig. 2 is an elevational view of the arrangement of Fig. 1; Fig. 3 represents the directional characteristic of the antenna; while Fig. 4 is a schematic representation of the antenna utilized in explaining its radiation properties.

Referring now more particularly to Fig. 1, the antenna system there represented is a directive horizontal loop. It is essentially diamond-shaped and comprises a pair of similar, coplanar radiating conductors of V-shaped configuration having an effective diameter d which is a substantial fraction of one-quarter of the operating wave length. The first conductor includes the sections or arms 10 and 11 while the other has arms 12 and 13. The conductors 10, 11 and 12, 13 are disposed in image relation with reference to a plane of symmetry so that the ends of one are spaced from the ends of the other, preferably by a distance which is comparable with the effective diameter of the conductor arms 10—13, inclusive. The separation of adjacent conductor ends is

usually in the range from one-half to twice the effective diameter. The arms of each conductor, for the case under consideration, are circular in cross section, being constituted of sections of highly conductive pipe or tubing, and have an electrical length approximately equal to one-quarter of the operating wave length, as indicated in Fig. 1. The arms 10 and 11 of the first conductor as well as the arms 12 and 13 of the other define an acute angle designated A while the remaining pair of angles of the loop, which occur at the open corners, are obtuse.

The horizontal loop antenna is equally useful for wave-signal transmission or reception. In either case, means are provided for connecting a wave-signal translating apparatus (not shown) with the antenna at only a single pair of the adjacent ends of conductors 10, 11 and 12, 13. This means is illustrated in the drawing as an open-wire transmission line TL connected with one pair of conductor ends, leaving the diagonally opposite pair of conductor ends open-circuited.

In the usual case, each of the conductor sections 10-13, inclusive, has an electrical length of one-quarter of the operating wave length, as indicated above, but this length may vary over a range from three-eighths to three-sixteenths of the operating wave length. The effective diameter d , which is said to be a substantial fraction of one-quarter of the operating wave length, is usually equal to one-twentieth of that wave length but may have any value within the range from one-tenth to one-fortieth. The acute angle A is one practical embodiment of the invention is equal to 45 degrees and is usually within a range of 30 to 60 degrees. However, it appears that the absolute limits of this angle are about 20 to 90 degrees.

The radiation characteristics of the antenna are represented by the curve of Fig. 3, which is a curve plotted on polar coordinates in terms of relative field strength. The antenna radiates horizontally polarized waves and is predominantly directive over a horizontal semi-circle facing the conductor ends to which the transmission line TL is connected. It exhibits minimum radiation in the direction of the other pair of conductor ends, as shown by the minor radiation extending in the opposite direction. Expressed differently, if the arrow F of Fig. 3 is considered to point to the forward direction of radiation, the backward radiation is substantially cancelled or attenuated. Consequently, the antenna has a substantial ratio of forward to backward radiation. This results from the physical aspects of the antenna as will be understood from the following discussion of the schematic representation of Fig. 4.

The open corners of the antenna represent points of current minimum and voltage maximum while current maximum and voltage minimum conditions are established at the closed corners, specifically, at the junctions of conductor sections 10, 11 and 12, 13. It is well known that a loop antenna composed of very thin conductors is highly resonant and therefore oscillates in substantially a pure standing wave but when thick conductors are employed, a traveling-wave current component is introduced. Hence the antenna of this invention has a predominantly standing-wave current component but also a minor traveling-wave current component. The traveling-wave component undergoes a phase variation in the antenna conductors so that the current in conductor section 10 has a leading phase with reference to that of the companion

conductor section 11. The extent of the phase change is determined by the conductor reactance and the radiation resistance. The reactance depends primarily on the thickness of the conductor sections while the radiation resistance is governed principally by the acute angle A defined by companion conductor sections. Thus, the antenna shape has two degrees of freedom which are selected, by utilizing physical dimensions of the order recited above, to effect approximate cancellation of radiation in the backward direction.

The selection of dimensions causes radiation from conductor section 10, for the instantaneous condition represented in Fig. 4, to produce a radiation component indicated by the vector V_1 . The slight leading phase of this radiation compensates for its longer path so that the vector V_1 is of substantially the same phase but opposite polarity relative to the radiation component, indicated by the vector V_2 , from the companion conductor section 11. Both vectors V_1 and V_2 represent back radiation, and since they are of opposite polarity they cancel one another. The leading phase of the current in conductor section 10 prevents cancellation in the forward direction of the components of radiation from the companion conductors 10 and 11. Therefore, these radiating elements aid one another in that direction. The other pair of conductor sections 12 and 13 may be analyzed in similar fashion to show that backward radiation from the system is effectively cancelled while forward radiation is augmented in accordance with the radiation characteristics represented by the curve of Fig. 3.

An ideal horizontal loop antenna gives cancellation of radiation in the vertical direction but the use of relatively thick conductor sections prevents complete cancellation and produces a minor component of vertical radiation. Two horizontal loops of the type shown in Fig. 1 stacked vertically with a spacing of one-half the operating wave length eliminate the vertical radiation.

The use of thick conductor sections minimizes the reactance of the antenna system so that it is only moderately frequency-selective. This feature permits operation over a moderate band of frequencies with small variations of impedance.

The described antenna has a very simple construction and may be easily mounted in a desired location. The use of relatively thick conductors to achieve the desired directivity is also desirable from the standpoint of mechanical rigidity.

For convenience, the foregoing description relates principally to the use of the antenna for wave-signal transmission. As already indicated, the functions of reception and transmission with any such antenna are unavoidably associated by the reciprocity theorem. Therefore, such terms as "radiating conductor," "radiation characteristics" and similar expressions are utilized in the text and appended claims in a generic sense to define an antenna structure in accordance with the invention whether that antenna be used for signal transmission or reception.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A resonant directive loop antenna system comprising: a pair of similar, coplanar radiating conductors of V-shaped configuration having an effective diameter substantially equal to one-twentieth of the operating wave length and disposed in image relation with reference to a plane of symmetry with the ends of one spaced from the ends of the other; one pair of said adjacent ends of said conductors having a highly reflecting termination and the arms of each conductor individually having an electrical length substantially equal to one-quarter of said wave length and defining an acute angle; and means for connecting signal-translating apparatus to said antenna at the other pair of said adjacent ends of said conductors, whereby said antenna system exhibits minimum radiation in the direction of the opposite pair of adjacent ends of said conductors.

2. A resonant directive loop antenna system comprising: a pair of similar, coplanar radiating conductors of V-shaped configuration and circular in cross section, having a diameter which is within the range from one-tenth to one-fortieth of the operating wave length and disposed in image relation with reference to a plane of symmetry with the ends of one spaced from the ends of the other; one pair of said adjacent ends of said conductors being open circuited and the arms of each conductor individually having an electrical length within the range from three-eighths to three-sixteenths of said wave length and defining an acute angle; and means for connecting signal-translating apparatus to said antenna at the other pair of said adjacent ends of said conductors, whereby said antenna system exhibits minimum radiation in the direction of the opposite pair of adjacent ends of said conductors.

3. A resonant directive loop antenna system comprising: a pair of similar, coplanar radiating conductors of V-shaped configuration having an effective diameter within the range from one-tenth to one-fortieth of the operating wave length and disposed in image relation with reference to a plane of symmetry with the ends of one spaced from the ends of the other; one pair of said adjacent ends of said conductors having a highly reflecting termination and the arms of each conductor individually having an electrical length substantially equal to one-quarter of said wave length and defining an acute angle; and means for connecting signal-translating apparatus to said antenna at the other pair of said adjacent ends of said conductors, whereby said antenna system exhibits minimum radiation in the direction of the opposite pair of adjacent ends of said conductors.

4. A resonant directive loop antenna system comprising: a pair of similar, coplanar radiating conductors of V-shaped configuration having an effective diameter which is within the range from one-tenth to one-fortieth of the operating wave length and disposed in image relation with reference to a plane of symmetry with the ends of one spaced from the ends of the other; one pair of said adjacent ends of said conductors having a highly reflecting termination and the arms of each conductor individually having an electrical length within the range from three-eighths to three-sixteenths of said wave length and defining an acute angle; and means for connecting signal-translating apparatus to said antenna at the other pair of said adjacent ends of

said conductors, whereby said antenna system exhibits minimum radiation in the direction of the opposite pair of adjacent ends of said conductors.

5. A resonant directive loop antenna system comprising: a pair of similar, coplanar radiating conductors of V-shaped configuration having an effective diameter which is within the range from one-tenth to one-fortieth of the operating wave length and disposed in image relation with reference to a plane of symmetry with the ends of one spaced from the ends of the other; one pair of said adjacent ends of said conductors having a highly reflecting termination and the arms of each conductor individually having an electrical length within the range from three-eighths to three-sixteenths of said wave length and defining an angle of substantially forty-five degrees; and means for connecting signal-translating apparatus to said antenna at the other pair of said adjacent ends of said conductors, whereby said antenna system exhibits minimum radiation in the direction of the opposite pair of adjacent ends of said conductors.

6. A resonant directive loop antenna system comprising: a pair of similar, coplanar radiating conductors of V-shaped configuration having an effective diameter which is within the range from one-tenth to one-fortieth of the operating wave length and disposed in image relation with reference to a plane of symmetry with the ends of one spaced from the ends of the other; one pair of said adjacent ends of said conductors having a highly reflecting termination and the arms of each conductor individually having an electrical length within the range from three-eighths to three-sixteenths of said wave length and defining an angle within the range from thirty to sixty degrees; and means for connecting signal-translating apparatus to said antenna at the other pair of said adjacent ends of said conductors, whereby said antenna system exhibits minimum radiation in the direction of the opposite pair of adjacent ends of said conductors.

7. A resonant horizontal directive loop antenna system comprising: a pair of similar, coplanar horizontal radiating conductors of V-shaped configuration having an effective diameter which is within the range from one-tenth to one-fortieth of the operating wave length and disposed in image relation with reference to a plane of symmetry with the ends of one spaced from the ends of the other; one pair of said adjacent ends of said conductors having a highly reflecting termination and the arms of each conductor individually having an electrical length within the range from three-eighths to three-sixteenths of said wave length and defining an acute angle; and means for connecting signal-translating apparatus to said antenna at the other pair of said adjacent ends of said conductors, whereby said antenna system exhibits minimum horizontal radiation in the direction of the opposite pair of adjacent ends of said conductors.

8. A resonant directive loop antenna system comprising: a pair of similar, coplanar radiating conductors of V-shaped configuration having an effective diameter which is within the range from one-tenth to one-fortieth of the operating wave length and disposed in image relation with reference to a plane of symmetry with the ends of one spaced from the ends of the other by a distance of the same order of magnitude as

said effective diameter; one pair of said adjacent ends of said conductors having a highly reflecting termination and the arms of each conductor individually having an electrical length within the range from three-eighths to three-sixteenths of said wave length and defining an acute angle; and means for connecting signal-translating apparatus to said antenna at the other pair of said adjacent ends of said conductors, whereby said antenna system exhibits minimum radiation in the direction of the opposite pair of adjacent ends of said conductors.
